UNITED STATES PATENT OFFICE

2,144,879

BEET TOPPER

Oscar J. Hallberg, Blackfoot, Idaho

Application March 4, 1937, Serial No. 129,060

3 Claims. (Cl. 146—85)

This invention appertains to new and useful improvements in beet topping machines and more particularly to a combination beet digger and topper.

The principal object of the present invention is to provide a machine which can be run along the ground for digging and elevating beets and subsequently topping the same in one continuous operation.

Another important object of the invention is to provide a combination machine of the character stated which will reduce handling of the beets to a minimum.

These and various other important objects and advantages of the invention will become apparent to the reader of the following specification.

In the drawings:

Figure 1 represents a side elevational view of the machine.

Figure 2 is a top plan view of the machine.

Figure 3 is a transverse vertical sectional view of the machine.

Figure 4 is a perspective view of one of the guide plate supporting brackets.

Figure 5 is a fragmentary vertical sectional view of one of the rear rollers for the belt.

Referring to the drawings wherein like numerals designate like parts, it can be seen in Figure 1 that numeral 5 represents the usual ground engaging element of the beet digger from which rises the conveyor belt 6 having the cleats 7 thereon and which is trained over the upper and lower rolls 8—9. This conveyor is also provided with the side walls 10 from which extends the draft means 11 and on which a driver's seat 12 can be mounted.

The topping apparatus proper is generally referred to by the numeral 13 and consists of the pair of rear wheels 14—14 and the forward wheels 15—15. The wheels 15 are attached to the forward axle 16 and a sprocket wheel 17 thereon drives the sprocket chain 18 which, in turn, drives the sprocket wheel on the shaft 19 carrying a gear 20 which, in turn, meshes with the pinion 21 on the shaft 22 of the upper roll 8. Thus the conveyor 6 is driven by the forward axle 16. A platform 22 is supported by the axle 16 and rising from each end of this platform 22 are the L-shaped bracket sections 24 to which the inverted L-shaped bracket members 25 are connected by bolt and slot connections 26 (see Figure 4). The upper horizontal portions of the sections 25 are secured to the undersides of the guide boards 27—27 between the adjacent edges of which the stems of beets are passable.

Mounted upon the forward end of the platform 23 are the rolls 28—28. These rolls are fixed while at the rear end of the platform 23 are the rolls 29—29 supported by the mounting 30 which is provided with a base portion 21 connected by 5 bolts 32 passing through the slot 33 in the platform 23. Thus the rear rolls 29 can be moved toward or away from each other to adjust the convergency of the inner flights 34 of the belts 35—36 which are horizontally trained over forward and rearward rolls 28—29.

Thus the beets elevated by the conveyor 6 are grasped by the attendant and inserted top downwardly between the belts 35—36 so that the beet heads ride along above the boards 27—27. The 15 cutter disk is denoted by numeral 35' and is mounted at the rear ends of the boards 27—27 in the path of the oncoming beet tops 36'. As the beets strike the cutting disk 35', the tops are severed from the heads and the tops fall downwardly from the machine while the heads are carried laterally and fall off onto the elevator 37 whereby the beet heads are elevated into a truck or other receptacle.

It can also be seen, that the axle 38 of the 25 rear wheels 14 carries a gear 39 meshing with the pinion 40 on a shaft with the gear 41 which, in turn, meshes with the worm 42 on the spindle of the cutting disk 35', the spindle passing through the upright post 43 mounted on the rear end of 30 the platform 23.

Furthermore, the rear axle 38 is equipped with a beveled gear 44 meshing with the beveled gear 45 on the shaft 46, the rear end of which is equipped with a sprocket over which a sprocket chain 47 35 is trained and engaged with a sprocket drive for the elevator 37.

Furthermore, it is to be understood that while the foregoing specification sets forth the invention in specific terms, it is to be understood that 40 numerous changes in the shape, size and materials may be resorted to without departing from the spirit and scope of the invention as claimed hereinafter.

Having described the invention what is claimed 45 as new is:

1. A beet topper comprising a pair of spaced conveyor belts arranged in edgewise vertical position for engaging and carrying beets by their tops with the heads thereof projecting above the conveyor, a pair of guide boards having their edges positioned in spaced relation above the conveyor, said boards supporting the heads of the beets in upright position and a cutter positioned horizontally above and adjacent the boards in 50 55

- the path of the beets at the discharge end of the conveyor.
2. A beet topper comprising a pair of spaced conveyor belts arranged in edgewise vertical position for engaging and carrying beets by their tops with the heads thereof projecting above the conveyor, a pair of guide boards having their edges positioned in spaced relation above the conveyor, said boards supporting the heads of the beets in upright position, means for adjusting the boards relative to the conveyor and a cutter positioned horizontally above and adjacent the boards in the path of the beets at the discharge end of the conveyor.
3. A beet topper comprising a horizontally disposed conveyor for engaging and carrying beets

by their tops with the heads thereof projecting above the conveyor, said conveyor comprising front and rear pair of rollers, belts trained over the rollers having one flight positioned in closely spaced relation with respect to the other, means for adjusting the rear rollers relative to each other to vary the space between the rear ends of the belts, a pair of guide boards having their edges positioned in spaced relation above the conveyor, said boards supporting the heads of the beets in upright position, means for adjusting the boards relative to the conveyor and a cutter positioned horizontally above and adjacent the boards in the path of the beet at the discharge end of the conveyor.

OSCAR J. HALLBERG. 15
